[57] CLAIM

The ornamental design for a liquid applicator with slide ring actuator, as shown and described.

DESCRIPTION

FIG. 1 is a perspective view of an applicator showing my new design;

FIG. 2 is a left side elevational view thereof;

FIG. 3 is a top plan view thereof;

FIG. 4 is a bottom plan view thereof;

FIG. 5 is a front elevational view thereof; and,

FIG. 6 is a rear elevational view thereof.

The right side of the applicator is a mirror image of the left side.
